UNITED STATES PATENT OFFICE.

JACOB JHON WALther, OF BOONVILLE, MISSOURI.

PILING.

No. 904,030.

Specification of Letters Patent.

Patented Nov. 17, 1908.

Application filed January 20, 1908. Serial No. 411,781.

To all whom it may concern:

Be it known that I, JACOB J. WALther, a citizen of the United States, residing at Boonville, in the county of Cooper and State 5 of Missouri, have invented certain new and useful Improvements in Piling, of which the following is a specification.

My invention relates to piles and walls formed thereby for protecting the banks of 10 rivers from the erosive action of the water, and has for its objects to provide an improved pile that may be readily sunk into position, will sink further in a predetermined direction when undermined, and will 15 not displace sidewise while sinking. These objects I accomplish in the manner and by the means hereinafter described and claimed, reference being had to the accompanying drawing, in which:—

20 Figure 1 is a sectional view of one bank of a river showing my improved piling in position. Fig. 2 is a similar view showing the bank washed away, and the piling in the act of sliding to a lower level. Fig. 3 25 is a view similar to Fig. 1 illustrating a slightly modified use of the invention. Fig. 4 is an enlarged detail elevation of the lower end of one of my improved piles. Fig. 5 is a sectional view on the line 5—5, Fig. 4. 30 Fig. 6 is a view similar to Fig. 1, showing still another use of the invention.

Like letters of reference in the several figures indicate the same parts.

The piles are preferably formed of reinforced concrete, though they may be made of metal or other suitable substance, and consist each of a body portion 1, rectangular in cross section and a V-shaped rib 2 formed integral therewith, and centrally disposed 35 longitudinally on said pile. The body portion 1 at its lower end is formed at a right angle to its length for about one half of its width, as shown at 3, merging into the angular surface 4 at an angle of about 45 degrees 40 thereto, which in turn merges into a less abrupt angular surface 5 formed on the lower end of the rib 2. Extending longitudinally through said pile are one or more through apertures 6, the same being for the 45 purpose of introducing hydraulic pressure therethrough, for the purpose of sinking the piles.

As shown in Fig. 1, a series of said piles are sunk side by side to form a protecting 50 wall said piles penetrating the ground at

the edge of the stream. While being sunk, whether by external or internal hydraulic pressure, the V-shaped rib 2 will bite into the bank and will cause said pile to descend in a straight line. Now, when in the course 60 of time the action of the stream washes away the bank in front of said piles, as shown in Fig. 2, the piles will remain in position, until the lower flat ends 3 thereof are uncovered, whereupon the angular surfaces 4 thereof will permit said piles to slide 65 forward and downward, this action being checked somewhat by the angular surfaces 5. The said sliding action will continue until the surfaces 5 lie substantially parallel with 70 the river bed, thus tilting the piles to an angle of about 60 degrees, in which position they will remain and will effectually protect the bank from further erosion.

In Fig. 1 I have shown the piles laid 75 against the bank with their lower ends above the water level, in which position they will remain until the bank beneath them is eaten away by the stream, whereupon they will slide down in a substantially vertical line 80 and gradually assume the position shown in dotted lines Fig. 2.

The ribs 2 perform the twofold function of aiding materially in driving the piling straight, and in preventing subsequent tipping or tilting to either side even under a 85 downward sliding movement.

It will be apparent that while said piles may be driven by external hydraulic pressure, the provision of the longitudinal apertures 6 for the passage of said pressure will permit of a straight driving thereof and with less pressure.

By reason of the ribs 2 I am enabled to drive a series of piles side by side to form a 95 protecting wall, and yet dispense with any tying together of said piles, so that each one thereof will be permitted an independent vertical movement and yet will be prevented by said ribs from any sidewise movement.

In Fig. 6 I have shown in full lines the piles 1 laid flat upon the river bank, and in dotted lines the position that will be assumed by said piles should the river wash away said bank. Thus, as the bank is gradually 105 washed away the piles will of their own weight gradually tip to the inclined position shown in dotted lines, thus protecting the bank against further erosion.

Having thus described my invention, what 110

I claim as new and desire to secure by Letters Patent, is:—

1. A pile, embodying a body portion having its lower end or bottom formed at a right angle to its length for a portion of its width, at an abrupt angle thereto for a portion of the rest of its width, and at a less abrupt angle for the remainder of its width.
2. A pile, embodying a body portion having a flat unbroken front side and a flat rear side, and a V-shaped rib formed centrally on said flat rear side and extending longitudinally of said body portion.
3. A pile, embodying a body portion and a rib extending longitudinally of said body portion, and connected thereto, said body portion having its lower end formed at a right angle to its length for a portion of its width and at a different angle thereto for

the rest of its width and said rib having its 20 lower end formed at a different and intermediate angle to those of said body portion.

4. The method of protecting banks, which consists in disposing a series of piles side by side upon said bank independent of each 25 other and partially embedded therein throughout their length, so that as said bank is washed away said piles will automatically assume a position to protect said bank below the level of the water and thus prevent 30 further erosion of said bank.

In testimony whereof I affix my signature, in presence of two witnesses.

JACOB JHON WALTHER.
